UNITED STATES PATENT OFFICE.

THOMAS L. LEE, OF ROCHESTER, NEW YORK, ASSIGNOR TO NORTH EAST ELECTRIC COMPANY, OF ROCHESTER, NEW YORK, A CORPORATION OF NEW YORK.

DESIGN FOR A CASING OF AN INDUCTION-COIL.

58,495.

Specification for Design.

Patented July 26, 1921.

Application filed December 24, 1917. Serial No. 208,718. Term of patent 14 years.

To all whom it may concern:

Be it known that I, THOMAS L. LEE, a citizen of the United States, residing at Rochester, in the county of Monroe and State of New York, have invented a new, original, and ornamental Design for a Casing of an Induction-Coil, of which the following is a specification.

In the accompanying drawings Figure 1 is a perspective view of a casing showing the design of the present invention; and Fig. 2 is a plan-view of the same.

The drawings show a casing comprising a body, a cover, a mounting-flange, and terminal-supports. The form and location of

the mounting-flange and of the terminal-supports are dictated by their mechanical and electrical functions, however, and will necessarily be varied according to considerations other than that of ornamental character. The ornamental feature of the design which it is intended particularly to set forth in this specification resides in the form of the body and the cover of the casing, said form comprising opposite salient portions, connected by cylindrically curved portions.

I claim:

The ornamental design for a casing of an induction-coil, as shown.

THOMAS L. LEE.
